(57) **CLAIM**

The ornamental design for a tray for a shower caddy, as shown and described.

DESCRIPTION

FIG. 1 is a front-left perspective view of a tray for a shower caddy of the claimed design;

FIG. 2 is a bottom-right perspective view of the tray for a shower caddy of FIG. 1;

FIG. 3 is a front view of the tray for a shower caddy of FIG. 1;

FIG. 4 is a top view of the tray for a shower caddy of FIG. 1;

FIG. 5 is a rear view of the tray for a shower caddy of FIG. 1;

FIG. 6 is a right side view of the tray for a shower caddy of FIG. 1;

FIG. 7 is a left side view of the tray for a shower caddy of FIG. 1; and,

FIG. 8 is a perspective view of an embodiment showing the tray for a shower caddy.

The broken lines shown in the figures represent portions of the tray for a shower caddy that form no part of the claimed design.

1 Claim, 5 Drawing Sheets
